UNITED STATES PATENT OFFICE

2,473,650

PHONOGRAPH PICKUP WITH MECHANICAL FILTER

Henry P. Kalmus, Chicago, Ill., assignor to Zenith Radio Corporation, a corporation of Illinois

Application June 10, 1943, Serial No. 490,296

2 Claims. (Cl. 179—100.4)

1

This invention relates to phonograph pickups. In many instances it is desirable to move an element of an electrical circuit and to produce linear electrical variations in the circuit in accordance with linear movement of the element. This is particularly true in frequency modulation apparatus wherein the element may form one element of a tuned circuit, and especially where it is desired that linear movement of the element should cause linear changes in resonant frequency of a circuit over a range corresponding to the range traversed by the instantaneous intensity of a signal in accordance with which there is displacement of such element.

In a phonograph pickup unit it is desirable in many instances to reproduce lateral, or hill and dale, recordings by varying the operating frequency of an associated electrical circuit. In that case the instantaneous resonant frequency of the circuit should bear a linear relationship to the amount of lateral, or hill and dale, displacement of a stylus in a groove of the recording.

Still another problem is that laterally cut recordings may be reproduced when they are mounted eccentrically on the rotating spindle and hill and dale recordings may be reproduced when the recording is in a warped condition. In such cases where the reproducing, or tone, arm translates the record groove undulations into a frequency change, very large changes of frequency may be produced at a low speed or at a low frequency less than 100 cycles, by such eccentricity or warping. Such large, low frequency, frequency deviations are undesirable primarily because of limitations in most frequency modulation reproducers, which commonly include a frequency deviation responsive device or frequency discriminator which produces a voltage whose instantaneous intensity is linearly proportional to the instantaneous frequency deviation of a wave, but only over a limited frequency range. It is therefore desirable that the effect of such eccentricity or warping upon the frequency deviation produced by the tone arm should be eliminated.

An object of my invention is to provide a new and improved phonograph pickup.

Another object of my invention is to provide a new and improved pickup unit whose response bears a linear relationship to record undulations having frequencies within the audio range but which is practically nonresponsive to frequencies corresponding to "wow," that is, eccentricity or warping, in phonograph records.

Another object of this invention is to provide

2

a pickup, or phonographic, arm which acts as a filter for reproducing undulations having frequencies above the frequencies corresponding to "wow," and rejecting those frequencies which correspond to "wow" in phonograph records.

The features of my invention which I believe to be novel are set forth with particularity in the appended claims. My invention itself, both as to its organization and manner of operation, together with further objects and advantages thereof, may best be understood by reference to the following description taken in connection with the accompanying drawings in which:

Fig. 1 shows apparatus which may be used in conjunction with invention;

Fig. 2 shows apparatus for receiving signals sent in accordance with my invention;

Fig. 3 is a graphical representation of certain characteristics of my invention;

Fig. 4 is a practical embodiment of one form of my invention;

Fig. 5 is a side view in elevation of a portion of the apparatus shown in Fig. 4;

Fig. 6 shows still another embodiment of my invention;

Fig. 7 shows a modified form of the invention, as illustrated in Fig. 6;

Figs. 8 and 9 show still another embodiment of my invention, Fig. 8 being a sectional view on line 8—8 of Fig. 9 and Fig. 9 being a sectional view taken on line 9—9 of Fig. 8;

Figs. 10 and 11 show yet another embodiment of my invention, Fig. 10 being a sectional view taken substantially on line 10—10 of Fig. 11 and Fig. 11 being a sectional view taken substantially on line 11—11 of Fig. 10.

Referring to the drawings wherein like reference numerals designate like parts in all figures, Fig. 1 shows a radio frequency transmitter adapted to transmit frequency modulated signals to a frequency modulation receiver, such as that shown in Fig. 2. The frequency of the wave transmitted from antenna 10 is determined by the reactances of the oscillator resonant circuit including inductance 11 in parallel with a circuit in which parallel connected capacitances 12 and 13 are in series with capacitance 14. The discharge device 15 is connected in a modified Colpitts oscillator circuit.

It is apparent that, if the inductance of coil 11 is varied, the frequency of oscillation is also varied. Variable capacitance 12 serves as a trimming capacitance for setting the oscillator at a predetermined frequency, about which it varies

as the inductance 11 is caused to vary. Coupling capacitance 16 serves to maintain one terminal of the previously described resonant circuit at the high frequency potential of the anode of discharge device 15, while blocking the flow of continuous current from the anode to the grid, or control electrode, of the discharge device 15. The other terminal of the resonant circuit is connected through condenser 19 to the grid of device 15 and the cathode is connected between 10 capacitances 13 and 14. Energy is supplied to the oscillator from voltage source or battery 17 which is connected in a series circuit with choke coil 18 between the anode and cathode of discharge device 15. The antenna 10 is connected directly to the anode of discharge device 15 and radiates energy having a frequency determined by the resonant circuit heretofore described.

In the frequency determining circuit the coil 11 is made with small inductance and the capacitances 12, 13 and 14 are of relatively high capacity, the two reactances resonating at the frequency of the wave transmitted. Capacitances 12, 13 and 14 are purposely made large so that the effects of varying amounts of stray capacitance are relatively small, as when the coil 11 is touched or moved manually. Resistance 20 connected between the grid and cathode of discharge device 15 serves to maintain the grid of tube 15 at a definite direct potential with respect to its cathode and thus stabilizes the operation of the discharge device. Coil 11 is adapted to move, as indicated by the arrows in Fig. 1, with respect to the copper and powdered iron discs 11A and 11B in a manner hereinafter described.

The apparatus shown in Fig. 2 serves as a receiver and frequency discriminator for frequency modulation signals, which are received from antenna 10 in Fig. 1. Continuous currents proportional to frequency changes in the mean frequency of the carrier wave transmitted from antenna 10 are indicated by direct current meter 21 and alternating voltages of frequency corresponding to the frequency of changes in the carrier frequency appear across the terminals 22 and 23.

The particular receiver or discriminator circuit shown in Fig. 2 is similar to one of a well-known type, described on page 197 of "Frequency Modulation" by A. Hund, McGraw-Hill Book Company, Inc., 1942. In brief, frequency modulation signals are received by antenna 24 and are impressed across a radio frequency transformer having a primary winding 25 and a secondary winding 26 tuned respectively by capacitances 27 and 28 to the mean or carrier frequency about which there are excursions of instantaneous carrier frequency. Coils 25 and 26 are loosely coupled and are excited at the frequency at which the oscillator of Fig. 1 operates when coil 11 is in its normal, or undisplaced, position. At that frequency, the voltage appearing across coil 25 is 90° out of phase with the voltage appearing across coil 26.

The purpose of the receiver or discriminator is to produce signals corresponding to frequency variations imposed upon the carrier frequency in response to motion of coil 11 which changes the carrier from its mean frequency. In order to cancel out effects due to amplitude variations of the carrier, the receiver or discriminator is made differentially acting by supplying a voltage, substantially in phase with the voltage appearing across coil 25, to the center tap of secondary winding 26. This in practice is done by connecting

capacitance 33 of low reactance between antenna 24 and the center tap of winding 26. With this connection, and with the cathode of diode 29 grounded for high frequency currents through capacity 35, a voltage appears across diode 29 which is equal to the vectorial sum of the voltage between antenna 24 and ground and half the 90° voltage induced in coil 26. The opposite ends of coil sections 26A and 26B are connected respectively to the anodes of diodes, or unidirectionally conducting devices, 29 and 30. The cathodes of rectifier devices 29 and 30 are grounded for high frequency currents, due to the fact that capacitance 35, of low reactance at the carrier or mean frequency, is connected between the cathodes and to ground. Also, the cathodes of rectifier or discharge devices 29 and 30 are connected in a series circuit including the equal resistances 31 and 32, serially connected. Lead line 36 connected between the center tap of coil 26 and the connection between resistances 31 and 32 represents a low resistance path for direct current flow between the output elements of the discharge devices 29 and 30.

With the balanced circuit thus far described it is clear that, when a signal is applied to antenna 24 with a frequency corresponding to the unmodulated carrier or mean frequency, the unidirectional rectified potentials appearing across equal resistances 31 and 32 are equal and are of such polarity that their net effect is zero on a continuous current meter 21, which is connected in parallel with the series circuit including those equal resistances. Resistance 34 in series with meter 21 serves to decrease the sensitivity of meter 21.

When a carrier wave of shifted frequency is received on antenna 24, rectified direct potentials appearing across resistances 31 and 32 are of unequal intensity and their net effect is to cause current to flow through meter 21 in a degree and direction depending upon the degree and amount of frequency shift of the carrier wave.

The inductance of coil 11 in Fig. 1 depends upon its position with respect to the discs of copper and powdered iron. Correspondingly, the frequency of radiation transmitted by antenna 10 is dependent upon the position of coil 11. The receiver and discriminator shown in Fig. 2 is so balanced that no current flows in meter 21 when coil 11 is equidistant from the copper disc and the powdered iron disc shown in Fig. 1. Displacements of coil 11 from the equidistant position cause corresponding deflections on instrument 21.

The inductance coil changes in inductance in a predetermined manner with its displacement. This is accomplished by mounting the coil so that its magnetic field encompasses a member having magnetic permeability greater than air and also encompasses a member having low resistance for the flow of electric current. In the absence of the powdered iron disc shown in Fig. 1, as coil 11 moves toward the copper disc, the effective inductance of coil 11 decreases. In the absence of the copper disc shown in Fig. 1, as the coil 11 moves toward the powdered iron disc, the effective inductance of coil 11 increases. Changes in effective inductance of coil 11 cause corresponding changes in frequencies transmitted by antenna 10.

This behavior is best illustrated in Fig. 3 wherein curve A represents the variation of transmitted frequency, in the direction of the arrow, when coil 11 is moved away from the

copper disc, the powdered iron disc being absent. Curve B represents the variation of transmitted frequency, in the direction of the arrow, as the coil 11 is moved away from the powdered iron disc, the copper disc being absent. Ordinate FO represents the frequency of transmission when both the copper disc and the powdered iron disc are absent. Curve C represents the variation of transmitted frequency when both copper and powdered iron discs are present and as coil 11 is moved relative to both the copper disc and powdered iron disc. Ordinate FW represents the carrier, or mean, frequency at which the transmitter in Fig. 1 normally operates when coil 11 is in its normal or undisplaced position, and the meter 21 in Fig. 2 reads "zero."

When interpreting Fig. 3 it is helpful to bear in mind that, when coil 11 is moved toward one of the discs (either copper or powdered iron), it moves away from the other disc. Curves A and B in Fig. 3 are non-linear and curve A has a positive curvature, whereas curve B has a negative curvature about equal to the positive curvature of curve A. That is, when only one of the discs is employed the antenna 10 radiates frequencies not linearly proportional to displacement of coil 11, and that non-linear proportionality is opposite for the two members 11A and 11B. However, when both the copper disc 11A and the powdered iron disc 11B are used, so that the inductance of coil 11 changes upon movement in accordance with curve C, linear movements of coil 11 cause corresponding substantially linear changes in frequency of the wave radiated by antenna 10.

Of course, every physical inductance coil possesses the properties of inductance and resistance. The magnitude of both of these properties of the coil are affected by the presence in the alternating magnetic field thereof of bodies possessing either magnetic or electricity conducting properties. That is, when a body such as copper is disposed in the alternating magnetic field of the inductance coil, due to the flow of eddy currents, the inductance of the coil is reduced but the effective resistance of the coil is increased and, consequently when and as the coil moves away from the copper body the coil inductance is increased but the effective coil resistance is decreased. Also, when a body such as a powdered iron core is disposed in the alternating magnetic field of the inductance coil, due to the permeability and hysteresis loss in the iron core the inductance of the coil as well as its resistance is increased and consequently, when and as the coil moves away from the iron core the coil inductance as well as the coil resistance is decreased. With these fundamental principles in mind, it is noted that in each one of the embodiments of my invention shown herein, where there is relative movement between an inductance coil and means (magnetic and conductive bodies) possessing magnetic and electricity conducting properties respectively, the inductance is increased or decreased as the case may be, depending upon the direction of relative movement, in a cumulative manner, but the effective resistance, being changed in a differential manner, tends to remain substantially constant during such relative movement. Inasmuch as the effective resistance of the relatively movable coil tends to remain constant, the modulation of the oscillator circuit including said coil is predominantly of the frequency type and the amount of amplitude modulation is much less

than that which would be present if either the copper or the powdered iron were taken out of the magnetic field of the coil. Hence, the present apparatus has the advantage that an amplitude limiting device of the type shown with similar apparatus in the copending application of Chalon W. Carnahan, Serial Number 406,431, filed August 11, 1941, now U. S. Patent No. 2,444,218, issued June 29, 1948, and assigned to the same assignee as the present application, is no longer deemed necessary for good reproduction of recordings and hence such limiting device is not shown herein in the phonograph arrangements.

Fig. 4 shows a practical construction embodying the variable inductance. A circular inductance coil 11 is snugly held in a recess in vibratile element 40, which has a hole 40A (see Fig. 5) therethrough for the passage of threaded bolt 41, which bolt rigidly joins spacers 42 and 43 and the ends of parallelly extending support members 44 and 45 with the vibratile element 40. One of the parallelly extending members 44 has a circular opening through its free end adapted to embrace and hold a solid copper cylinder 46. The other parallelly extending member 45 has a similar cylindrical opening through its free end adapted to embrace and hold a solid cylinder of powdered iron, such as is commonly formed of iron particles cemented with a suitable binder. The copper cylinder 46, circular coil 11 and cylindrical iron core 47 are mounted coaxially. The vibratile element 40, parallelly extending members 44 and 45, and spacers 42 and 43 may be of polystyrene or other similar plastic material. Vibratile element 40 is made sufficiently long and of such small cross section so as to follow undulations in a laterally cut phonograph record, when the stylus 48 is in a groove of the laterally cut phonograph record. In other words, the arm 40 is made inherently flexible and resilient enough to allow movement of inductance coil 11 relative to the cylinders 46 and 47.

As seen from Figs. 4 and 5, the vibratile element 40 has a portion 40B of reduced cross section so that the vibratile element has a large compliance for horizontal movement of the element 40 in Fig. 4 and a small compliance for movement of the stylus 48 in the plane of the paper in Fig. 5. Thus, the arm 40, due to its shape, responds more readily to laterally cut undulations in a phonograph record than to hill and dale cut undulations in the same phonograph record.

Fig. 6 shows a tone arm in which the vibratile inductance unit shown in Figs. 4 and 5 may be mounted. The tone arm proper of Fig. 6, in conventional manner, is mounted for pivotal movement about a pivot (not shown), so that it may freely move across a record toward its center as the stylus 48 moves in a convolution or spiral groove of a record R. The tone arm shown in Fig. 6 comprises rigid supporting member 51, which rotates around the vertical pivot (not shown) in conventional manner, and a filter element 52 connecting the supporting member 51 to a head 53. Head 53 encloses the variable inductance unit shown in Fig. 4. The unit shown in Fig. 4 may be fastened to the head 53 by means of screws 54, which are threaded in tapped holes 55 (Fig. 4) in the spacers 42 and 43.

In this embodiment of my invention the filter element 52 comprises a thin strip of metal lying in a vertical plane and having its opposite ends rigidly fixed to member 51 and head 53, respec-

tively. The compliance of filter element 52 bears definite relationship to the compliance of vibratile element 40, as is hereinafter explained.

The vibratile element 40 is stiff enough and the filter element 52 is weak enough, so that, taken with the mass of head 53, when the vibratile element 40 oscillates horizontally in Fig. 4 at a frequency less than a predetermined low frequency, for example, 100 cycles per second, the head 53 moves with respect to member 51 at the corresponding low frequency without relative movement between vibratile element 40 and parallelly extending members 44 and 45 (see Fig. 4) carried by head 53. When the vibratile element 40 moves laterally in Fig. 4 at a rate greater than the predetermined low frequency, the filter element 52 has not sufficient compliance and mass of head 53 is too great at those frequencies to allow head 53 to move with respect to member 51 and, as a consequence, the vibratile element 40 moves relative to the parallel extending members 44 and 45 carried by head 53 at frequencies above the predetermined low frequency.

Thus, by proper design of vibratile element 40, head 53, and filter element 52, frequencies corresponding to "wow" frequencies encountered in playing phonograph records are substantially eliminated without loss of fidelity.

With the tone arm construction shown in Figs. 4-6, hill and dale imperfections in a record cause little effect on the inductance of coil 11, since the vibratile element 40 is much more flexible for lateral movement of the element 40 in Fig. 4 than for movement in the plane of the paper in Fig. 5, and since substantially equal and opposite inductance changes are produced in coil 11 by copper cylinder 45 and powdered iron cylinder 47, even if the vibratile element 40 does move in a direction corresponding to hill and dale movement.

Since the frequency determining circuit including coil 11 is of the high capacity type, substantial changes of stray, or body, capacitances have little effect on the frequency of the wave transmitted. Consequently, if desired, some or all of the elements shown in Fig. 1 may be mounted in the tone arm head 53. The size of present day vacuum tubes or discharge devices permits the tube or device 15 of Fig. 1 to be mounted in the head of a tone arm, along with a high capacity tuned circuit, similar to the one shown in Fig. 1.

Fig. 7 shows a modified filter element of the type shown in Fig. 6. The filter elements 52A and 52B, each approximately of one-half the width of filter element 52 in Fig. 6, mechanically join the head 53 to the tone arm extension 51, so as to produce exactly the same mechanical effect as element 52. In addition, the mechanical filter elements 52A and 52B are held in spaced relationship to one another so that they form a pair of electrical current conductors for the passage of current through the inductance coil 11 in the tone arm head 53.

In the arrangement shown in Figs. 8 and 9, which are sectional views of the same assembly taken at right angles to each other and on different scales, the vibratile element 150 is adapted to follow undulations in a laterally cut phonograph record. The vibratile element 150, having inductance coil 11 snugly held in a circular opening therethrough, is suspended within the tone arm head, or housing, 151 by flexible connecting means 152 and 153. Each of the flexible means 152 and 153 may be a resilient wire or thin

strip of metal or other resilient material, the induced stresses remaining in the range of elasticity.

In the preferred form the flexible connecting means 152 and 153 allows the vibratile element 150 in Fig. 8 to move with greater freedom in the horizontal direction than in the vertical direction, whereby the composite pickup unit moves more in response to laterally cut undulations in a phonograph record, than to imperfections in a phonograph record having indentations or mounds thereon corresponding to hill and dale variations. However, due to the arrangement of the discs and coil, the effective inductance of coil 11 is unaltered by hill and dale movement. The flexible connecting means 152 and 153 may have such compliance as to allow the housing 151, within which the element 150 is suspended, to be connected to the free end of filter element 52 in Fig. 6 in place of head 53.

When so mounted, the compliance of springs 152 and 153, which support vibratile element 150, bears a definite relationship to the compliance of filter elements 52. That is, the mass of element 150 and the compliance of springs 152 and 153 are such that record undulations of all desired frequencies cause motion of element 150 with respect to housing 151, but the mass of housing 151 and the compliance of spring 152 are such that, at frequencies lower than those desired and corresponding to "wow" in phonograph records, the housing 151 moves as a whole together with element 150, so that such low frequency undulations produce no relative movement between vibratile element 150 and housing 151.

The tone arm head or housing 151, shown in Figs. 8 and 9, has a U-shaped cross section and upon its inner walls semicircular copper and powdered iron discs are fastened by suitable means, for example, by means of screws 155. The semicircular copper and powdered iron discs are disposed so that semicircular discs of unlike material are on opposite sides of coil 11 at the top edge and also at the bottom edge, and so that semicircular discs of unlike material are adjacent the top and bottom coil edges on each side, as shown in Fig. 8. As the coil 11 rotates about its center of gravity, one coil edge approaches copper and recedes from iron while the opposite coil edge approaches iron and recedes from copper.

The arrangement shown in Figs. 10 and 11 is adapted to reproduce sound recordings from records having hill and dale impressions thereon. In this arrangement, the springs 159 and 160 have such form that the vibratile element 150 has greater flexibility for vertical movement than for horizontal movement, so that imperfections corresponding to lateral cuts on a phonograph record are reproduced with relatively small amplitude.

It is important to note that semicircular discs of like material are disposed on opposite sides of the top edge and also on the bottom edge of coil 11 but with semicircular discs of unlike material disposed adjacent the top and bottom coil edges on one side of element 150. As the vibratile element 150 moves in a vertical direction under the influence of hill and dale impressions in a phonograph record, up and down movement of coil 11 in element 150 places it alternately nearer copper and nearer iron, so that its inductance alternately decreases and increases, respectively. Furthermore, due to the arrangement of coil 11 and associated semicircular discs of copper and powdered iron, the inductance of coil 11 remains substantially unaffected by horizontal movement of coil

11, since changes in inductance produced by any one of the semicircular discs is compensated by a corresponding opposite change produced by another semicircular disc.

The parts shown in Figs. 10 and 11, with the exception of flexible connecting means 159 and 160, are similar to corresponding parts shown in Figs. 8 and 9. The flexible connecting means 159 and 160 may be thin strips of metal having a greater resistance to bending along one of its axes than along its other axis. That is, the thin strip lies in a horizontal plane. When the inductance unit 11 is made responsive to hill and dale recordings by mounting it as shown in Figs. 10 and 11, the filter element 52 (Fig. 6) connected between the tone arm extension 51 and head 53 has its transverse axes rotated through 90° and has such compliance with respect to the compliance of connecting means 152 and 153 that frequencies corresponding to "wow" frequencies are not reproduced.

In the various modifications of my invention, I have shown means for causing a predetermined variation of inductance of coil 11 so as to cause predetermined frequency changes in a tuned circuit as a function of linear inductance coil movement. In order to produce such changes in frequency of the tuned circuit, the corresponding variation of inductance is not necessarily linear, since the frequency of a tuned circuit varies inversely as the square root of inductance. The variation of inductance in the arrangements herein disclosed is due to the algebraic sum of two distinct variations, i. e., curve C in Fig. 3 is the algebraic sum of curves A and B, and either curve A or curve B or both curves A and B may be changed by suitably dimensioning or spacing the powdered iron and copper members which are associated with coil 11. Thus, with the means herein disclosed, the effective inductance of coil 11 as a function of its movement may have other desired variations than the particular variation which produces linear changes in the frequency of a tuned circuit. For instance, the effective inductance of coil 11 may be made to vary linearly with its movement.

While I have shown and described the particular embodiments of my invention, it will be obvious to those skilled in the art that changes and

modifications may be made without departing from my invention in its broader aspects, and I, therefore, aim in the appended claims to cover all such changes and modifications as fall within the true spirit and scope of my invention.

I claim:

1. In a phonograph pickup, a supporting arm, a pickup head, a mechanical filter element connected between said arm and head, a vibratile member supported in said head, and electrical circuit connections including said filter element electrically connected with said vibratile member.

2. In a phonograph pickup, a supporting arm, a pickup head, a mechanical filter element between said arm and said head, said head including a movable coil, a stylus pivoted about an axis spaced from its record engaging tip and having mounted thereon said coil centered substantially around said axis, whereby the coil is pivoted about an axis corresponding substantially to an axis passing through a center of gravity when and as the stylus travels in the undulations of a record groove.
